UNITED STATES PATENT OFFICE.

ALBERT G. CUMMINGS, OF HARRISBURG, ASSIGNOR TO THE PENNSYLVANIA STEEL COMPANY, OF STEELTON, PENNSYLVANIA.

SAFETY APPLIANCE FOR RAILWAYS.

SPECIFICATION forming part of Letters Patent No. 276,564, dated May 1, 1883.

Application filed January 12, 1883. (No model.)

To all whom it may concern:

Be it known that I, ALBERT G. CUMMINGS, a citizen of the United States, residing at Harrisburg, in the county of Dauphin and State of Pennsylvania, have invented certain new and useful Improvements in Safety Appliances for Railways; and I do declare the following to be a full, clear, and exact description of the invention, such as will enable others skilled in the art to which it appertains to make and use the same, reference being had to the accompanying drawings, and to letters of reference marked thereon, which form a part of this specification.

My invention relates to the use of switches in railway-tracks and arrangements for operating such switches in connection with signals, for the purpose of rendering it impossible for trains moving in disregard of danger-signals to come in collision with other trains for which safety-signals have been given.

In my former patent, No. 226,499, dated April 13, 1880, I have shown a system of interlocking levers for switches and signals by which the signals are locked to indicate "danger" until all conflicting signals have been set and locked, so that a switch or signal operator cannot show safety-signals for two interfering lines of tracks at the same time; but when a combination of tracks has been provided with such a system of interlocking levers, although it will be impossible for the signal-man to display safety-signals for two interfering lines of tracks at the same time, there is danger that careless train-men may move their trains in disregard of stop or danger signals and run across tracks for which safety-signals have been given to other trains, and thus cause collisions to take place, and it is the object of my invention to remove such danger, and to render such collisions impossible by the use of switches so set in the track used by a train approaching a point of possible collision (in disregard of danger-signals) that said train will by said switch be prevented from continued movement into a line of track for which safety-signals have been given.

In the drawings, Figure 1 is a diagram of tracks A, B, C, D, E, F, and G, with signals and switches. Fig. 2 represents a single-point-

Referring to Fig. 1, A and B represent two main lines of a double-track railroad on which trains will generally move in the direction indicated by the arrows; and C and D represent two lines of single-track railroad on which trains move in both directions. B², C¹, C², E, and F represent side and branch tracks connecting to the above-mentioned tracks by means of switches A², B³, C³, C⁶, and D³. C¹, C⁵, D¹, and D² represent "throw-off switches," by which the tracks C¹, C², and D may be broken and rendered impassable for trains. H represents the lines of connections from the various switches to interlocking levers by means of which the switches are to be operated, said levers being arranged in the cabin N, as is customary in such cases. The connections to signals are not shown. 1 represents the signal for track B. 2 and 3 represent signals for track A. 4, 5, and 6 represent the signals for track D. 7, 8, 9, and 10 represent signals for track C, C¹, and C².

In Fig. 2, I show details of a form of throw-off switch which I prefer to use, the single point-rail O of such form as to fit properly against a stock-rail, P, the normal position of the point-rail O being such as to gage with the main-line rail S and bear against the stock-rail P. The stock-rail P is made to lead away from the line of track, so that when the point-rail O is moved away from the stock-rail P into the reversed position any wheels running on said stock-rail P toward the heel of the switch will drop off said rail P. When the point-rail O is in its normal position against the stock-rail P it is secured by a lock-bolt, L, passing through an opening in the switch-rod K, and operated by means of a rod, R, which will be connected to a safety or detector bar, preferably such as described in my Patent No. 271,803, of February 6, 1883, said lock and bar being operated by an interlocking lever in the cabin N.

All of the switches I have mentioned will be provided with similar arrangement of lock-bolts and safety-bars operated by interlocking levers. With a system of interlocking levers for the operation of the switches, signals, &c., the normal position of the levers usually is that in which all the switches are

closed—*i. e.*, set for the main line—and the signals all indicate “danger,” and to take a train through will require, first, to set the certain switches that will turn aside trains coming up 5 on the conflicting lines in disregard of danger-signals, or open the switches that will prevent their movement altogether; second, to lock the certain switches that will be passed over by the train proceeding properly, and then and 10 only then to set the proper signal to “safety.” The hand-lever of this signal will be interlocked with the other hand-levers, so that it will be impossible to move them or change the position of the switches, &c., until the signal 15 has been returned to “danger,” when other combinations may be effected in like manner.

Let it be supposed that a train is to be taken through on track B, Fig. 1; the operation will be as follows: Switch C³ will be opened, so 20 that if a train on track C should run past signals 7 and 8 it would go onto track F; switches C⁴ and C⁵ will be opened, so that if trains on tracks C' or C² should run past their respective signals 9 and 10 they would be derailed; 25 switches D' and D² will be opened, so that if trains on track D should run past their respective signals 4, 5, or 6 they would also be derailed; then switch B³ is locked, and finally the signal 1 will be set to indicate “safety,” 30 and the train on track B can proceed. The reversing of the hand-lever of signal 1 will lock all of the hand-levers for said switches C³, C⁴, C⁵, D', and D² and prevent their change until the signal 1 is returned to “danger.” While 35 switch C³ is opened, as above mentioned, the signal 8 may be cleared to allow movements between track F and the portion of track C outside of switch C³. Or, let it be supposed that a train is to pass from point D⁴ of the track 40 D over tracks E, A, and G and proceed on track B in the direction indicated by arrow; the operation will be as follows: the switch C³ will be opened, so that if a train on track C should run past signals 7 and 8 it would be diverted onto track F; switches C⁴ and C⁵ will 45 be opened, so that if trains on tracks C' or C² should run past their respective signals 9 and 10 they would be derailed, and switch D² will be opened, so that if a train on track D should run past signal 6 it would be derailed; switch B³ will be opened and locked, so that 50 if a train on track B should run past signal 1 it would be diverted onto track B² and prevented from coming into collision with a train 55 on the route we have in view. The levers of switches B' and B³ are interlocked, so that the movement of switch B³ is required to release switch B'; next, the switches A' and B' will be opened and locked, the switches A² and D³ 60 will be opened and locked, the switch D' will be locked, and finally the signal 4 will be set to indicate “safety,” and the hand-levers of all conflicting signals and diverting-switches thereby locked in their positions, and the train 65 will proceed over the aforesaid route.

It will be noticed that the switches B³ and B' face outward in opposite directions from

that portion of the track B over which passage of trains is to be prevented in the movement just described, and that the switch B³ 70 must be set to break the track B to allow the switch B' to be set to form a junction of the track G with the track B.

Having fully explained the arrangement and operation of the switches and signals for two 75 movements, it will be apparent that other movements as may be required can be provided for in a similar manner.

In the movements above described it will be noticed that the switches C³ and B³, besides 80 their usual functions, serve as “safety” elements of importance when they are operated by interlocking levers in the manner described, and are made parts of the combinations as I have above mentioned. It will be noticed, 85 also, that by use of the throw-off switches C⁴, C⁵, D', and D², operated by interlocking levers and combining their operation in the manner described, I have secured a means of controlling the movements of trains that may 90 be carelessly run past danger-signals that does effectually prevent such trains from collision with other trains which are proceeding in due accordance with safety-signals; also, that such throw-off switches may be used in any 95 system of tracks when interlocked with the signals, so that a track or any part thereof may be effectually prevented from improper movements of trains, and the manner of placing or using switches for such purposes will 100 be readily understood by those skilled in such matters, and need not be more particularly described in this specification.

Although the interlocking mechanism I have used is that described in my Patent No. 226,499, 105 I do not confine myself to the use of that particular design of interlocking apparatus, as the purposes of my invention may be effected by the use of any pattern or design of interlocking mechanism which will so interlock 110 switch and signal levers that one lever will control the movement of other levers.

I am aware of the use of throw-off switches in side tracks to prevent accidental movement into main tracks of cars on such side tracks, 115 also of the use of throw-off switches operated singly by hand-levers at the switch, the same having no connection with other switches or other signals; but I am not aware of their use in the manner I have described; and 120

I claim as my invention—

1. The combination, with crossing tracks and signals therefor, of an interlocking mechanism and a throw-off switch or switches, whereby the crossing line or lines of tracks 125 must be broken to allow a safety-signal to be given, substantially as and for the purpose specified.

2. The combination, with crossing main lines, of a turn-out and switch and interlocking mechanism requiring the switch in one line to be set to the turn-out before a safety-signal is given to the other line, substantially as and 130 for the purpose set forth.

3. The combination, with a line of track, a switch facing in one direction breaking said line, and a branch leading into it beyond said break, of a switch facing in the opposite direction, by which said branch connects with said line of track, and an interlocking mechanism governing said switches, whereby said

line of track is broken for protection of trains to or from the branch, substantially as and for the purpose specified.

ALBERT G. CUMMINGS.

In presence of—

S. W. FLEMING,
ED. M. COOPER.
